[57] ABSTRACT

Compounds having sex hormonal activity consisting of

steroid compounds possessing a 17 β -oxygen function and being substituted in the 17 α -position by a group of the structure

wherein

R¹ is selected from the group consisting of carbocyclic aryl, aralkyl, heterocyclic having 5 or 6 members and containing at least one hetero atom selected from O, N and S, alicyclic, alkenyl having two-five carbon atoms and alkyl having one-five carbon atoms;

R² is selected from the group consisting of hydrogen, carbocyclic aryl, aralkyl, heterocyclic having 5 or 6 members and containing at least one hetero atom selected from O, N and S, alicyclic, alkenyl having two-five carbon atoms and alkyl having one-five carbon atoms; or

R¹ and R² together with the carbon atom to which they are attached form an alicyclic ring.

The compounds exhibit an unusual separation of oestrogenic and anti-fertility activities (in rats) compared with ethynodiol.

7 Claims, No Drawings

17A-(5'-SUBSTITUTED-5'-HYDROXY-PENTA-1',
3'-DIYNYL)-STEROIDS

This invention is concerned with improvements in or relating to steroids having sex hormonal activity.

We have found that by modifying the structure of steroids having sex hormonal activity in the way hereinafter specified, new compounds having modified sex hormonal properties may be produced. Such compounds exhibit, for example, oestrogenic or progestational properties, and are of value in human and veterinary medicine for the treatment of a wide range of conditions and defects of the reproductive system and for the limitation or enhancement of fertility.

According to the invention there are provided compounds having sex hormonal activity consisting of steroid compounds possessing a 17β -oxygen function and being substituted in the 17α -position by a group of the structure

wherein

R^1 is a carbocyclic aryl group, an aralkyl group, a heterocyclic group, an alicyclic group, an alkenyl group having two-five carbon atoms or an alkyl group having one-five carbon atoms;

R^2 is hydrogen, a carbocyclic aryl group, an aralkyl group, a heterocyclic group, an alicyclic group, an alkenyl group having two-five carbon atoms or an alkyl group having one-five carbon atoms; or

R^1 and R^2 together with the carbon atom to which they are attached form an alicyclic ring.

The term "steroid" is used herein to denote compounds having a nucleus derived from perhydro-1,2-cyclopentenophenanthrene. Since the compounds according to the invention are structurally related to compounds possessing sex hormonal activity they will ordinarily possess an oxygen function, e.g., hydroxy, methoxy or oxo, at the 3-position; they will ordinarily possess unsaturation in ring A of an olefinic or aromatic character, but may be ring A-saturated; they will ordinarily possess a lower alkyl group at C_{13} and may or may not have a methyl group at C_{10} . These functions are generally found in a variety of sex hormones to a greater or lesser extent although sex hormones devoid of, for example, a 3-oxygen function are known to exist.

The compounds according to the invention possess a 17η -oxygen function i.e., a 17β -hydroxy group or an ester or ether group thereof, e.g., a lower alkoxy group or a lower alkanoyloxy group.

By "sex hormonal activity" is meant activity of an oestrogenic, gestogenic or androgenic nature and includes such activity produced by naturally occurring steroids as well as by steroids not known to exist in nature. The sex hormonal activity may be directly present in the compound or may be manifested in vivo by biological transformation of the compound. The term also includes activity manifested as anti-hormonal activity although the compounds in question possess some degree of normal hormonal activity e.g., a compound possessing residual oestrogenic activity may function as an anti-oestrogen.

R^1 and R^2 may, where their definitions permit, be the same or different.

When R^1 or R^2 is a carbocyclic aryl group this may be mono- or bi-cyclic and when it is bicyclic the rings may be fused. R^1 or R^2 may thus be phenyl, 1- or 2-naphthyl or o- or p-biphenyl. One may use a carbocyclic aryl group in an unsubstituted form or such a group substituted by, for example, one or more fluorine, chlorine or bromine atoms, hydroxy groups, alkyl groups containing one-five carbon atoms, or trifluoromethyl groups. Examples of such substituted carbocyclic aryl groups include p-tolyl, o-chlorophenyl, o- and p-methoxyphenyl.

When R^1 or R^2 is an aralkyl group the aryl moiety or moieties may be a mono- or bi-cyclic carbocyclic group, substituted or unsubstituted, as explained above, and the alkyl moiety may contain one-five carbon atoms. Examples of such aralkyl groups include benzyl and phenethyl.

When R^1 or R^2 is a heterocyclic group it may be a 5- or 6-membered ring containing one or more hetero atoms selected from O, N and S. It may be aromatic or non-aromatic. Examples of such heterocyclic groups include 2- or 3-pyridyl and 2- or 3-thienyl.

When R^1 or R^2 is an alicyclic group it may be, for example, cyclohexyl or adamantyl, while when R^1 or R^2 is alkenyl it may, for example, be vinyl, propenyl or isopropenyl.

When R^1 or R^2 is an alkyl group it may e.g. be a methyl, ethyl, propyl, isopropyl, n- or sec- butyl or n-pentyl group.

When R^2 represents hydrogen R^1 is preferably a carbocyclic aryl group, a heterocyclic group, an alicyclic group or an alkenyl group.

The compounds of the invention may be derived from any 17-keto or 17β -oxygen function-containing steroid compound having sex hormonal activity. In general, but not exclusively, such compounds will contain unsaturation and/or substituents in rings A and B.

Thus the compounds according to the invention may contain unsaturation as one or more Δ^1 , Δ^2 , Δ^3 , Δ^4 , Δ^5 , $\Delta^{5(10)}$, Δ^6 , Δ^7 , Δ^8 and Δ^9 . For example, ring A may be aromatic or may contain Δ^4 or Δ^2 unsaturation. Again unsaturation may be present in or shared with rings A and B e.g. as $\Delta^{4,6}$ or $\Delta^{5(10)}$ or ring A may be aromatic and ring B may contain 1 or 2 double bonds.

Rings A and B may contain one or more substituents selected from acyloxy, alkoxy, alkyl and alkenyl (each containing up to 5 carbon atoms), halogeno, hydroxy and oxo. One or more of these substituents may be so chosen that they are metabolised in vivo to give unsaturation.

Ring C may be devoid of substituents or may, for example, contain an oxygen or halogen (i.e., chloro or bromo) function at C_{11} .

The compounds according to the invention include 19-nor compounds as well as 10-methyl compounds. They also include 13-methyl, -ethyl and -propyl compounds.

The compounds of the invention may, for example, belong to the androstan, 19-norandrostane (or oestrane), 18-methyoestrane or 18-ethyoestrane series.

Compounds of the invention which are of particular interest are those which exhibit oestrogenic and/or progestational activity; such compounds may be used in the control of fertility.

An important compound according to the invention is 17α -(5-hydroxy-5-methyl-1,3-hexadiynyl)-3-methoxy-1,3,5(10)-oestratrien-17 β -ol which is a potent oestrogen many times more active than ethynodiol as evidenced by vaginotrophic assay. This compound may be administered at a daily dosage of from 1 to 10 μ g in association with a progestational compound, e.g., megestrol acetate at a daily dosage of from 2 to 5 mg, to women for 21 days during each menstrual cycle for the avoidance of fertility.

Compounds of this invention show an unusual separation of oestrogenic and anti-fertility activities in the experimental rat, in comparison with ethynodiol. The oestrogenic potency, determined in the conventional uterotrophic assay, is found to be small relative to the anti-fertility activity. The oestrogenic potency determined in the vaginotrophic assay, is significantly greater than in the uterotrophic assay and corresponds more closely to the anti-fertility activity. A separation of potency between uterotrophic and vaginotrophic assays, relative to ethynodiol is quite unexpected.

A compound which, in the human, showed anti-fertility activity greater than corresponds to its overall hormonal activity offers advantages in oral contraceptive preparations in terms of decreased side-effects and increased safety, compared with ethynodiol, at present widely used in such preparations.

Important compounds according to the invention by virtue of the separation of their oestrogenic and anti-fertility activities include

- a. 17α -(5-hydroxy-5-phenyl-1,3-pentadiynyl)-3-methoxy-1,3,5(10)-oestratrien-17 β -ol;
- b. 17α -(5-hydroxy-5-p-tolyl-1,3-pentadiynyl)-3-methoxy-1,3,5(10)-oestratrien-17 β -ol;
- c. 17α -(5-hydroxy-5-(2-naphthyl)-1,3-pentadiynyl)-3-methoxy-1,3,5(10)-oestratrien-17 β -ol;
- d. 17α -(5-hydroxy-5-o-chlorophenyl-1,2-pentadiynyl)-3-methoxy-1,3,5(10)-oestratrien-17 β -ol;
- e. 17α -(5-hydroxy-5-cyclohexyl-1,3-pentadiynyl)-3-methoxy-1,3,5(10)-oestratrien-17 β -ol;
- f. 17α -(5-hydroxy-p-biphenyl-1,3-pentadiynyl)-3-methoxy-1,3,5(10)-oestratrien-17 β -ol; and
- g. 21α -(5-hydroxy-5-methyl-1,3-hexadiynyl)-3-methoxy-1,3,5(10)-oestratrien-17 β -ol

of which compounds (b), (d) and (f) show very significant separation in respect of these activities.

Compounds according to the invention exhibiting significant anti-fertility activity include 17β -(5-hydroxy-1,3-hexadiynyl)-4-androsten-17 β -ol-3-one and 17α -(5-hydroxy-5-methyl-1,3-hexadiynyl)-4-oestren-17 β -ol-3-one.

The compounds of the invention may be prepared by any suitable method. However, a further aspect of the invention provides a process for the preparation of said compounds which comprises reacting a mixture of an ethynyl compound

and a haloethynyl compound

wherein one of R^3 , R^4 is a steroid moiety to which the ethynyl or haloethynyl group is linked in the α -configuration at the 17-position and the other of R^3 and R^4 is the group

5

wherein R^1 and R^2 have the above-defined meanings in the presence of a cuprous salt, whilst maintaining said cuprous salt in the reduced state.

- 10 It is advantageous to employ a catalytic quantity of the cuprous salt, which is preferably a cuprous halide e.g., cuprous chloride, although other cuprous salts (e.g., the acetate) may be used. The two ethynyl reactants may be used in approximately equivalent proportions, or one may be in moderate excess. It is desirable to carry out the reaction in the presence of a base to assist the desired reaction and to take up hydrogen bromide. Where the base is a relatively strong organic base, e.g., a lower alkylamine such as ethylamine or triethylamine it may fulfil both functions; where it is a relatively weak organic base it should be used in association with an inorganic base, e.g., powdered sodium hydroxide or powdered calcium carbonate.
- 15

In order to maintain the cuprous salt in a reduced state, a reducing agent is desirably present in the reaction mixture. A preferred reducing agent is hydroxylamine or a salt thereof. It is advantageous to perform the reaction in an inert atmosphere, e.g., nitrogen.

Suitable temperatures for the reaction range between -10 and $30^\circ C$, preferably -5 to $+5^\circ C$.

The reaction is greatly assisted by a suitable reaction medium, which should be sufficiently polar to dissolve at least a minor amount of the cuprous salt of the ethynyl compound $R^3 - C \equiv CH$. It is not necessary for the reactants to be completely in solution but the reaction appears to take place in solution! It is highly desirable for the reaction medium to contain water. Suitable reaction media include lower alcohols (e.g. methanol or ethanol) or their mixtures with dimethylformamide, dimethylacetamide or dimethylsulphoxide, a proportion of water being present.

When the reaction is complete, a reagent, e.g., potassium cyanide, may be added to react with any residual acetylenic cuprous compound, and the steroid product may be removed by any convenient work-up procedure. For example the reaction mixture may be diluted with water and filtered or extracted with a solvent such as ether. Final purification may be by chromatography and/or recrystallisation.

50 When the steroid starting material contains an oxo group, such group may require protection from any reducing agent present in the reaction mixture. This may be achieved by converting the oxo group into, e.g., an enol ether, enamine, ketal, thioketal or oxime. Conveniently an excess of hydroxylamine may be used as reducing agent, whereby the oxo group is converted into an oxime. Thereafter the oxo group may be regenerated as desired. However, it may be found that an oxo group is not attacked to a sufficient extent to warrant protecting it.

Compounds according to the invention containing a 17β -hydroxy group may be prepared by reacting a 17 -oxo steroid with a compound of the general formula

65

wherein R¹ and R² are as defined above and M is Li, Na, K or Mg Hal (wherein Hal = Cl, Br or I), and subsequently regenerating the desired derivative from the resulting complex. If M is Na, K or MgHal protection of the OH group of the acetylenic compound, e.g., by prior conversion into a tetrahydropyranyl ether, may be advantageous. The desired derivative is obtained by regeneration from the resulting complex by conventional procedures.

A still further method of preparing compounds according to the invention comprises treating a metal derivative (e.g., a Grignard reagent) of a 17 α -(buta-1,3-diylyn) steroid compound with an aldehyde or ketone of the general formula R¹R²CO, where R¹ and R² are as defined above.

Where the compound obtained according to the invention is a 17 β -hydroxy compound the latter may then be esterified or etherified. This may result in simultaneous esterification or etherification of the OH group in the 17 α -chain.

The invention also includes within its scope pharmaceutical compositions comprising one or more compounds according to the invention together with a pharmaceutical carrier or excipient. Such compositions may also include one or more further active compounds, e.g. other sex hormones. For example, compounds having progestational activity may advantageously be formulated in conjunction with one or more hormones having oestrogenic activity.

The compositions according to the invention are intended for administration to both humans and animals. The term "pharmaceutical" as used herein to describe compositions and carriers means therefore that these are of use in both human and veterinary medicine.

The compositions are preferably in the form of dosage units and may be formulated for daily oral administration in such forms as tablets, capsules, sachets etc., either for taking directly or with a draught. Suppositories for rectal absorption may also be employed. Injection preparations may be formulated, preferably for more prolonged action, while implantation pellets may be formulated having the advantage of requiring very infrequent administration.

Conventional pharmaceutical excipients for solid preparations may for instance include sugar alcohols, sugars, starch, magnesium stearate, gelatine, polyethylene glycols and suitable colouring agents. Tablets may be coated for protection, colour distinction or elegance by conventional methods such as film coating or sugar or pearl coating. Suppositories may be prepared, using conventional bases such as glyco-gelatine, cocoabutter, or water-dispersible bases with a melting point above body temperature, such as polyglycols.

For injection purposes, preparations for intramuscular or subcutaneous administration may be prepared in conventional sterile oily, aqueous or emulsion bases, in solution and/or suspension. Vehicles preferably include physiologically acceptable vegetable oils, e.g., arachis oil, fractionated coconut oil; oily esters, e.g., isopropyl myristate; non-aqueous solvents, e.g., propylene glycol; aqueous vehicles such as sterile water or physiological saline; together with suitable formulation agents such as suspending agents, e.g. aluminium stearate for oily materials, carboxymethyl cellulose for aqueous preparations; physiologically acceptable emulsifying agents,

e.g., "Tween" 81, buffering agents for pH control, anti-oxidants, stabilising and solubilising agents. The injections may be formulated for immediate use, or as a dry powder for re-constitution before use with a separate vehicle. Unit injections required for prolonged action, e.g., 1 month's duration, would naturally contain an increased quantity of active material.

Each dosage unit for daily administration to humans preferably contains 1 μ g to 5 mg active material according to the invention depending on the condition being treated and the potency of the compound.

Implantation pellets would in general contain a much higher dosage to cover prolonged activity for preferably several months. Implants may be prepared aseptically from sterile material, by fusion or heavy compression, preferably without the addition of other substances.

For veterinary use in particular, long acting vaginal inserts such as tampons and pessaries, may be prepared in a conventional manner. The dosage required for animal treatment will of course, vary according to the size of the animal.

The progestational compounds of the invention may be employed as oral contraceptives, preferably either in daily doses of 0.1 mg to 5 mg on approx. 21 days in each menstrual cycle along or mixed with an oestrogen, e.g., ethynodiol 0.05 or 0.1 mg. Apart from their use as oral contraceptives, progestagens may be employed clinically in the following conditions; dysmenorrhoea, functional uterine bleeding, premenstrual tension, diagnosis of pregnancy, and endometriosis.

In order that the invention may be better understood, the following examples are given by way of illustration only.

Example 1

17 α -(5-Hydroxy-5-phenyl-1,3-pentadiynyl)-3-methoxy-1,3,5(10)-oestratrien-17 β -ol

A solution of ethynodiol (3.4 ml) in N,N-dimethyl-formamide (40 ml) was added to a stirred mixture of cuprous chloride (0.38 g), hydroxylamine hydrochloride (0.86 g), methanol (47 ml), N,N-dimethyl-formamide (80 ml), and 70% aqueous ethylamine (9.7 ml) and the mixture was stirred for 1 hour under nitrogen at room temperature. It was then cooled to 0°C and 17 α -bromoethynyl-3-methoxy-1,3,5(10)-oestratrien-17 β -ol in N,N-dimethylformamide (87 ml) was added during 1 hour. The mixture was allowed to warm to room temperature, stirred for 2 hours, treated with potassium cyanide (1.0 g) in water (11 ml), and poured into water (67 ml). The precipitate was collected and crystallised from a mixture of ether and light petroleum (b.p. 60 – 80°) giving 17 α -(5-hydroxy-5-phenyl-1,3-pentadiynyl)-3-methoxy-1,3,5(10)-oestratrien-17 β -ol, m.p. 134° [α]_D²⁴ -46° (C-1.2 in dioxan), λ_{max} 287.5 nm (ϵ , 2000), 278 nm (ϵ , 2100), 246.5 nm (ϵ , 1100).

Example 2

17 α -(5-Hydroxy-5-p-tolyl-1,3-pentadiynyl)-3-methoxy-1,3,5(10)-oestratrien-17 β -ol

Sodium (23 g) was added to liquid ammonia (1 litre) during passage of a stream of acetylene, to form the mono-sodium derivative of acetylene. p-Tolualdehyde (120 g) in tetrahydrofuran (500 ml) was added and the mixture stirred under reflux, with continued passage of acetylene, for 3 hours. The ammonia was allowed to evaporate and the residue treated with water, acidified

65

and extracted with ether. Distillation of the ether layer gave ethynyl-p-tolyl-carbinol b.p. 78°/0.3mm.

A solution of ethynyl-p-tolyl-carbinol (3.89 g) in N,N-dimethylformamide (53 ml) was added to a stirred mixture of cuprous chloride (0.47 g), hydroxylamine hydrochloride (1.03 g), methanol (57 ml), N,N-dimethylformamide (96 ml) and 70% aqueous ethylamine (12 ml) and the mixture was stirred for 1 hour under nitrogen at room temperature. It was then cooled to 0°C and a solution of 17 α -bromoethynyl-3-methoxy-1,3,5(10)-oestratrien-17 β -ol (8.0 g) in N,N-dimethylformamide (104 ml) was added during 30 minutes; after a further 10 minutes at 0°C, the mixture was allowed to warm to room temperature during 30 minutes. Potassium cyanide (1.32 g) in water (14.5 ml) was added and the mixture poured into ice/water. The precipitate was collected and crystallised from a mixture of benzene and light petroleum (b.p. 60 – 80°), giving 17 α -(5-hydroxy-5-p-tolyl-1,3-pentadiynyl)-3-methoxy-1,3,5(10)-oestratrien-17 β -ol m.p. 154°, $[\alpha]_D^{23}$ -43.6° (C-0.3 in dioxan), λ_{max} 277.5 nm (ϵ , 2173), 286.5 nm (ϵ , 1968).

Example 3

a. Preparation of ethynyl-(2-naphthyl)-carbinol.

Ethyl magnesium bromide, prepared from ethyl bromide (30.0 g) and magnesium (6.8 g), in tetrahydrofuran (175 ml) was added during 2 hours to a saturated solution of acetylene in tetrahydrofuran (150 ml). The mixture was stirred for 2 hours during continued passage of acetylene. 2-Naphthaldehyde (25.0 g) was added and the mixture heated under reflux for 1 hour and allowed to cool. Saturated aqueous ammonium chloride solution (50 ml) was then added to the mixture which was extracted with ether. Distillation of the ether layer gave ethynyl-2-naphthyl-carbinol b.p. 148 – 150°/0.75 mm recrystallised from benzene, m.p. 61°, b. 17 α -(5-Hydroxy-5-(2-naphthyl)-1,3-pentadiynyl)-3-methoxy-1,3,5(10)-oestratrien-17 β -ol.

A solution of ethynyl-(2-naphthyl)carbinol (5.0 g) in N,N-dimethyl-formamide (53 ml) was added to a stirred mixture of cuprous chloride (0.47 g), hydroxylamine hydrochloride (1.03 g), methanol (57 ml), N,N-dimethyl-formamide (96 ml), and 70% aqueous ethylamine (12 ml) and the mixture was stirred for 1 hour under nitrogen at room temperature. The mixture was cooled to 0°C and a solution of 17 α -bromoethynyl-3-methoxy-1,3,5(10)-oestratrien-17 β -ol (8.0 g) in N,N-dimethylformamide (104 ml) was then added during 20 minutes. After a further 10 minutes at 0°C, the mixture was allowed to warm to room temperature during 30 minutes. A solution of potassium cyanide (1.32 g) in water (14.5 ml) was then added and the mixture poured into ice/water. The precipitate was collected and crystallised from a mixture of benzene and light petroleum (b.p. 60 – 80°), giving 17 α -(5-hydroxy-5-(2-naphthyl)-1,3-pentadiynyl)-3-methoxy-1,3,5(10)-oestratrien-17 β -ol, m.p. 114° $[\alpha]_D^{23}$ -39.8° (C-0.3 in dioxan) λ_{max} 267.5 nm (ϵ , 7850), 247.75 nm (ϵ , 4900) 275.5 nm (ϵ , 6650), 285.5 nm (ϵ , 4850).

Example 4

17 α -(5-Hydroxy-5-o-chlorophenyl-1,3-pentadiynyl)-3-methoxy-1,3,5(10)-oestratrien-17 β -ol.

A solution of o-chlorophenyl-ethynyl-carbinol (4.75 g) in N,N-dimethylformamide (65 ml) was added to a stirred mixture of cuprous chloride (0.47 g), hydroxylamine hydrochloride (1.03 g), methanol (57 ml), N,N-dimethylformamide (96 ml) and 70% aqueous

ethylamine (12 ml) under nitrogen at room temperature. The mixture was cooled to 0°C and a solution of 17 α -bromoethynyl-3-methoxy-1,3,5(10)-oestratrien-17 β -ol (8.0 g) in N,N-dimethylformamide (104 ml) was added during 25 minutes. After a further 10 minutes at 0°C, the mixture was allowed to warm to room temperature during 45 minutes when a solution of potassium cyanide (1.32 g) in water (15 ml) was added and the mixture poured into ice/water. The precipitate was collected and crystallised from cyclohexane. Removal of retained solvent in vacuo at 68° gave amorphous 17 α -(5-hydroxy-5-o-chlorophenyl-1,3-pentadiynyl)-3-methoxy-1,3,5(10)-oestratrien-17 β -ol $[\alpha]_D^{24}$ -36° (C, 0.3 in dioxan) λ_{max} 247.5 nm (ϵ , 1400), 263.5 nm (ϵ , 1600), 278 nm (ϵ , 2200), 287.5 nm (ϵ , 2000).

Example 5

17 α -(5-Hydroxy-5,5-diphenyl-1,3-pentadiynyl)-3-methoxy-1,3,5(10)-oestratrien-17 β -ol.

A solution of 17 α -ethynyl-3-methoxy-1,3,5(10)-oestratrien-17 β -ol (9.2 g) in N,N-dimethylformamide (50 ml) was added to a stirred mixture of cuprous chlroide (0.43 g), hydroxylamine hydrochloride (1.01 g), methanol (52 ml), N,N-dimethylformamide (84 ml) and 70% aqueous ethylamine (13.6 ml) and the mixture was stirred under nitrogen at room temperature for 1 hour. A solution of 1-bromo-3,3-diphenyl-1-propyn-3-ol (5.4 g) (W. Chodkiewicz, Annales de Chimie 2, 819 1957) in N,N-dimethylformamide (50 ml) was added during 1 hour. The mixture was stirred for 1½ hours, treated with a solution of potassium cyanide (1.2 g) in water (50 ml), and poured into water. The precipitate was collected and purified by chromatography on silica gel, eluting with toluene/ethyl acetate. Crystallisation from cyclohexane gave 17 α -(5-hydroxy-5,5-diphenyl-1,3-pentadiynyl)-3-methoxy-1,3,5(10)-oestratrien-17 β -ol containing cyclohexane of crystallisation, m.p. 96 – 97°, $[\alpha]_D^{23}$ -35.7° (C-0.47 in dioxan), λ_{max} 287 nm (ϵ , 1782), 277 nm (ϵ , 1927), 261.5 nm (ϵ , 1544), 247.5 nm (ϵ , 1452).

Example 6

a. Preparation of 17 α -bromoethynyl-6 β -methyl-5 α -androstan-3 β , 5,17 β -triol.

Silver nitrate (15.0 g) was added to a solution of 17 α -ethynyl-6 β -methyl-5 α -androstan-3 β , 5,17 β -triol (15.0 g) in ethanol (700 ml) and water (210 g). The mixture was stirred for 45 minutes, N-bromosuccinimide (15.0 g) was added, the mixture stirred for a further 5 minutes and poured into 5% aqueous sodium bicarbonate solution (3 litres). The precipitate was collected and purified from methylene chloride and acetone/light petroleum (b.p. 60-80°), giving 17 α -bromoethynyl-6 β -methyl-5 α -androstan-3 β , 5,17 β -triol, m.p. 201°, $[\alpha]_D^{28}$ -52.3° (C-0.25 in EtOH). b. 17 α -(5-Hydroxy-5-phenyl-1,3-pentadiynyl)-6 β -methyl-5 α -androstan-3 β , 5,17 β -triol

A solution of ethynyl-phenyl-carbinol (4.0 ml) in N,N-dimethylformamide (40 ml) was added to a stirred mixture of cuprous chloride (0.45 g), hydroxylamine hydrochloride (1.00 g), methanol (55 ml), N,N-dimethyl-formamide (95 ml) and 70% aqueous ethylamine (10.7 ml) and the mixture was stirred for 1 hour under nitrogen at room temperature. The mixture was cooled to 0°C and a solution of 17 α -bromoethynyl-6 β -methyl-5 α -androstan-3 β , 5,17 β -triol (8.0 g) in N,N-dimethylformamide (110 ml) was added during 1

hour. The mixture was allowed to warm to room temperature, stirred for 2 hours, treated with a solution of potassium cyanide (1.2 g) in water (70 ml), and poured into water (700 ml). The precipitate was collected and crystallised from ether/light petroleum and aqueous methanol, giving 17α -(5-hydroxy-5-phenyl-1,3-pentadiynyl)- 6β -methyl- 5α -androstan- 3β , 5 , 17β -triol, m.p. 175° $[\alpha]_D^{20}$ -54.3° (C-0.5 in EtOH); λ_{max} 299.5 nm (ϵ , 331.7), 283 nm (ϵ , 413.7), 259 nm (ϵ , 867.5), 247 nm (ϵ , 1039).

Example 7

17α -(5-Hydroxy-5-(1-naphthyl)-1,3-pentadiynyl)-3-methoxy-1,3,5(10)-oestratrien- 17β -ol.

A solution of ethynyl-(1-naphthyl)-carbinol (0.49 g) in N,N-dimethylformamide (5.0 ml) was added to a stirred mixture of cuprous chloride (0.047 g), hydroxylamine hydrochloride (0.103 g), methanol (5.7 ml), N,N-dimethylformamide (9.6 ml), and aqueous ethylamine (1.2 ml; 70%), and the mixture was stirred for 1 hour under nitrogen at room temperature. The mixture was cooled to 0°C and a solution of 17α -bromoethynyl-3-methoxy-1,3,5(10)-oestratrien- 17β -ol (0.80 g) in N,N-dimethylformamide (10.0 ml) was added during 10 minutes, and stirring continued at 0°C for a further 10 minutes. A solution of potassium cyanide (0.13 g) in water (2.0 ml) was added and the mixture poured into water. The precipitate was collected and crystallised from cyclohexane giving 17α -(5-hydroxy-5-(1-naphthyl)-1,3-pentadiynyl)-3-methoxy-1,3,5(10)-oestratrien- 17β -ol, containing cyclohexane of crystallisation, m.p. ill-defined, $[\alpha]_D^{26}$ -33° (C-0.25 in dioxan) λ_{max} 272 nm (ϵ , 9700), 281.5 nm (ϵ , 11900), λ_{inf} 262.5 nm (ϵ , 6200), 286.5 nm (ϵ , 9100), 292 nm (ϵ , 7150).

Example 8

17α -(5-Hydroxyl-5-cyclohexyl-1,3-pentadiynyl)-3-methoxy-1,3,5(10)-oestratrien- 17β -ol.

A solution of ethynyl-cyclohexyl-carbinol (2.65 g) in N,N-dimethylformamide (30 ml) was added to a stirred mixture of cuprous chloride (0.28 g), hydroxylamine hydrochloride (0.64 g), methanol (35 ml), N,N-dimethylformamide (60 ml), and 70% aqueous ethylamine (7.2 ml) and the mixture was stirred under nitrogen for 1 hour at room temperature. The mixture was cooled to 0°C and a solution of 17α -bromo-ethynyl-3-methoxy-1,3,5(10)-oestratrien- 17β -ol (5.0 g) in N,N-dimethylformamide (70 ml) added during 80 minutes, when stirring was continued at 0°C for 1½ hours. A solution of potassium cyanide (0.74 g) in water (9 ml) was added and the mixture poured into water. The precipitate was collected and crystallised from cyclohexane giving 17α -(5-hydroxy-5-cyclohexyl-1,3-pentadiynyl)-3-methoxy-1,3,5(10)-oestratrien- 17β -ol, containing cyclohexane of crystallisation m.p. ill-defined, $[\alpha]_D^{23}$ -36.3° (C, 0.4 in dioxan), λ_{max} 261 nm (ϵ , 831), 278 nm (ϵ , 1911), 287.5 nm (ϵ , 1804).

Example 9

17α -(5-Hydroxy-5-o-methoxyphenyl-1,3-pentadiynyl)-3-methoxy-1,3,5(10)-oestratrien- 17β -ol

A solution of ethynyl-o-methoxyphenyl-carbinol (3.37 g) in N,N-dimethylformamide (40 ml) was added to a stirred mixture of cuprous chloride (0.35 g), hydroxylamine hydrochloride (0.78 g), methanol (43 ml), N,N-dimethylformamide (73 ml) and 70% aqueous ethylamine (8.8 ml) and the mixture was stirred for 1 hour at room temperature, under nitrogen. The mixture was cooled to 0°C , and a solution of 17α -bromoethynyl-3-methoxy-1,3,5(10)-oestratrien- 17β -ol (0.80 g) in N,N-dimethylformamide (10 ml) was added during 5 minutes. The mixture was stirred for 1 hour at

bromoethynyl-3-methoxy-1,3,5(10)-oestratrien- 17α -ol (6.08 g) in N,N-dimethylformamide (79 ml) was added during 80 minutes. The mixture was stirred for 2 hours at 0°C and for 1 hour at room temperature. A solution of potassium cyanide (1.0 g) in water (11 ml) was added and the mixture poured into water. The precipitate was collected and purified by crystallisation from ether/cyclohexane giving 17α -(5-hydroxy-5-o-methoxyphenyl-1,3-pentadiynyl)-3-methoxy-1,3,5(10)-oestratrien- 17β -ol, containing cyclohexane of crystallisation, m.p. ill-defined, $[\alpha]_D^{22}$ -22.5° (C- 0.4 in dioxan), λ_{max} 220 nm (ϵ , 20500), 246.2 nm (ϵ , 1950), 277 nm (ϵ , 5400).

Example 10

a. Preparation of p-biphenyl-ethynyl-carbinol.

Ethyl magnesium bormide, prepared from ethyl bromide (12.0 g) and magnesium (2.7 g) in tetrahydrofuran (50 ml) was added during 30 minutes to a saturated solution of acetylene in tetrahydrofuran (60 ml).

The mixture was stirred for 1 hour during continued passage of acetylene. A solution of p-phenylbenzaldehyde (8.5 g) in tetrahydrofuran (40 ml) was then added and the mixture heated under reflux for 1 hour and allowed to cool. Saturated aqueous ammonium chloride solution (25 ml) was then added and the mixture extracted with ether. The ether layer was washed, dried (Na_2SO_4) and freed from solvent at reduced pressure. Crystallisation of the residue from benzene/light petroleum (b.p. $60-80^\circ$) gave p-biphenyl-ethynyl-carbinol, m.p. $117-8^\circ$ λ_{max} 253.5 nm (ϵ , 21517).

b. 17α -(5-Hydroxy-5-p-biphenyl-1,3-pentadiynyl)-3-methoxy-1,3,5(10)-oestratrien- 17α -ol.

A solution of p-biphenyl-ethynyl-carbinol (5.8 g) in N,N-dimethylformamide (65 ml) was added to a stirred mixture of cuprous chloride (0.47 g), hydroxylamine hydrochloride (1.03 g), methanol (57 ml), N,N-dimethylformamide (96 ml) and aqueous ethylamine (12 ml; 70%) and the mixture was stirred for 1 hour under nitrogen at room temperature. The mixture was cooled to 0°C and treated with a solution of 17α -bromethynyl-3-methoxy-1,3,5(10)-oestratrien- 17β -ol (8.0 g) in N,N-dimethylformamide (104 ml) added during 25 minutes. The mixture was stirred at 0°C for 10 minutes

and for 1 hour while warming to room temperature, treated with a solution of potassium cyanide (1.2 g) in water (10 ml), and poured into water ($2\frac{1}{2}$ litres). The precipitate was collected and crystallised from methylene chloride/light petroleum (b.p. $60-80^\circ$) giving 17α -(5-hydroxy-5-p-biphenyl-1,3-pentadiynyl)-3-methoxy-1,3,5(10)-oestratrien- 17β -ol, m.p. 119° , $[\alpha]_D^{23}$ -39.8° (C, 0.33 in dioxan), λ_{max} 220 nm (ϵ , 18800), 232.5 nm (ϵ , 14435), 255 nm (ϵ , 24410).

Example 11

17α -(5-Hydroxy-5-p-methoxyphenyl-1,3-pentadiynyl)-3-methoxy-1,3,5(10)-oestratrien- 17β -ol.

A solution of ethynyl-p-methoxyphenyl-carbinol (0.443 g) in N,N-dimethylformamide (5 ml) was added to a stirred mixture of cuprous chloride (0.047 g), hydroxylamine hydrochloride (0.103 g), methanol (5.7 ml), N,N-dimethylformamide (9.6 ml), and 70% aqueous ethylamine (1.2 ml) and the mixture was stirred for 1 hour at room temperature under nitrogen. The mixture was cooled to -20°C , and a solution of 17α -bromoethynyl-3-methoxy-1,3,5(10)-oestratrien- 17β -ol (0.80 g) in N,N-dimethylformamide (10 ml) was added during 5 minutes. The mixture was stirred for 1 hour at

-15 to -20°C and poured into water. The precipitate was collected and purified by chromatography on alumina, eluting with cyclohexane/ethyl acetate mixture. Crystallisation from cyclohexane gave 17α -(5-hydroxy-5-p-methoxyphenyl-1,3-pentadiynyl)-3-methoxy-1,3,5(10)-oestratrien-17 β -ol, containing cyclohexane of crystallisation, m.p. 106°C, $[\alpha]_D^{23}$ -30.5° (C, 0.15 in dioxan); λ_{max} 230 nm (ϵ , 22700), 276 nm (ϵ , 4600), 281 nm (ϵ , 4200); λ_{inf} 286.5 nm (ϵ , 3100).

Example 12

17α -(5-Hydroxy-5-methyl-1,3-hexadiynyl)-3-methoxy-1,3,5(10)-oestratrien-17 β -ol

A solution of 2-methyl-3-butyn-2-ol (3.00g) in N,N-dimethylformamide (50 ml) was added to a stirred mixture of cuprous chloride (0.43 g), hydroxylamine hydrochloride (1.01g), methanol (52 ml), N,N-dimethylformamide (84 ml), and 70% aqueous ethylamine (13.6 ml), and the mixture was stirred for 1 hour under nitrogen at room temperature. 17α -Bromoethynyl-3-methoxy-1,3,5(10)-oestratrien-17 β -ol (8.00 g) in N,N-dimethylformamide was added during 1 hour. After a further 10 minutes, potassium cyanide (1.2 g) in water (15 ml) was added and the mixture was poured into water. The precipitate was collected and purified by crystallisation from a mixture of di-iso-propyl ether and light petroleum (60-80°) and from aqueous methanol, giving 17α -(5-hydroxy-5-methyl-1,3-hexadiynyl)-3-methoxy-1,3,5(10)-oestratrien-17 β -ol, containing water of crystallisation, m.p. 104°C, $[\alpha]_D^{24}$ - 53.6° (C, 0.41 in dioxan), λ_{max} 287.7 nm (ϵ , 2000), λ_{max} 278.5 nm (ϵ , 2200).

Example 13

17α -(5-Hydroxy-5-phenyl-1,3-pentadiynyl)-1,3,5(10)-oestratriene-3,17 β -diol

Silver nitrate (2.00 g) was added to a stirred solution of 3-acetoxy-17 α -ethynyl-1,3,5(10)-oestratrien-17 β -ol (2.00 g) in a mixture of ethanol (100 ml) and water (30 ml) and the mixture was stirred at room temperature for 35 minutes. N-Bromosuccinimide (2.00 g) was added and the mixture was stirred for 5 minutes and then poured into aqueous sodium bicarbonate solution. The precipitate was collected and crystallised from aqueous methanol giving 3-acetoxy-17 α -bromoethynyl-1,3,5(10)-oestratrien-17 β -ol, m.p. 176°C, $[\alpha]_D^{23}$ - 13.5° (C, 0.68 in dioxan).

Ethynyl-phenyl-carbinol (5.0 ml) was added to a stirred mixture of cuprous chloride (0.60g), hydroxylamine hydrochloride (1.40 g), methanol (70 ml), N,N-dimethylformamide (120 ml) and 70% aqueous ethylamine (14.6 ml) and the mixture was stirred for 1 hour under nitrogen at room temperature. It was then cooled to 0°C and 3-acetoxy-17 α -bromoethynyl-1,3,5(10)-oestratrien-17 β -ol (10.00g) in N,N-dimethylformamide (130 ml) was added during 1 hour. The mixture was allowed to warm to room temperature, stirred for 2½ hours, treated with acetic acid (20 ml) in water (150 ml) and poured into water (2.1). The precipitate was collected and purified by chromatography on an alumina column, eluting with a mixture of toluene and ether, giving 17α -(5-hydroxy-5-phenyl-1,3-pentadiynyl)-1,3,5(10)-oestratriene-3,17 β -diol, m.p. 174-177°C, $[\alpha]_D^{23}$ - 49.8° (C, 0.41 in dioxan), λ_{inf} 286 nm (ϵ , 2150), λ_{max} 281 nm (ϵ , 2400).

Example 14

17α -(5-Hydroxy-5-methyl-1,3-hexadiynyl)-1,3,5(10)-oestratriene-3,17 β -diol

2-Methyl-3-butyn-2-ol (0.60 g) in N,N-dimethylformamide (13 ml) was added to a stirred mixture of cuprous chloride (0.116 g), hydroxylamine hydrochloride (0.26 g), methanol (14 ml), N,N-dimethylformamide (24 ml) and 70% aqueous ethylamine (3.0 ml) and the mixture was stirred at room temperature for 45 min. and then cooled to 0°C. 3-Acetoxy-17 α -bromoethynyl-1,3,5(10)-oestratrien-17 β -ol (2.40 g) in N,N-dimethylformamide (25 ml) was added during 6 - 7 min. at 0°C.

10 After a further 5 min. potassium cyanide (0.33 g) in water (5ml) was added and the mixture was poured into water. The precipitate was collected and treated with potassium hydroxide (2.0 g) in ethanol (50 ml) and water 20 ml) at room temperature for 15 min. The solution was poured into water containing a slight excess of hydrochloric acid, and the precipitate was collected and dried. Purification by crystallisation from methylene chloride/ cyclohexane gave 17α -(5-hydroxy-5-methyl-1,3-hexadiynyl)-1,3,5(10)-oestratriene-3,17 β -diol, m.p. 140-145°C (ill-defined), λ_{max} 280 nm (ϵ , 2100) $[\alpha]_D^{23}$ -50.7° (C, 0.37 in dioxan), λ_{inf} 285 nm (ϵ , 790), 285.3 nm (ϵ , 1950).

Example 15

17α -(5-Hydroxy-1,3-hexadiynyl)-3-methoxy-1,3,5(10)-oestratrien-17 β -ol

55% Aqueous 1-butyn-3-ol (1.30 ml) was added to a stirred mixture of cuprous sulphite (0.10 g), hydroxylamine hydrochloride (0.15 g), methanol (12 ml), water (4 ml), and 70% aqueous ethylamine (3.4 ml) and the mixture was stirred at room temperature under nitrogen for 45 min. and then cooled to 0°C. 17α -Bromoethynyl-3-methoxy-1,3,5(10)-oestratrien-17 β -ol (1.95 g) in methanol (50 ml) was added during 45 min.

30 After a further 15 min. potassium cyanide (0.30 g) in water (3 ml) was added and the mixture was poured into water. The steroid product was isolated by extraction with ether and purified by crystallisation from methylene chloride/cyclohexane, affording 17α -(5-hydroxy-1,3-hexadiynyl)-3-methoxy-1,3,5(10)-oestratrien-17 β -ol, m.p. 129-134°C, $[\alpha]_D^{24}$ - 40.8° (C, 0.37 in dioxan) λ_{max} 277 nm (ϵ , 2215), 286.5 nm (ϵ , 1860).

Example 16

3-Cyclopentyloxy-17 α -(5-hydroxy-5-methyl-1,3-hexadiynyl)-1,3,5(10)-oestratrien-17 β -ol

3-Cyclopentyloxy-17 α -ethynyl-1,3,5(10)-oestratrien-17 β -ol (3.50g.) in N,N-dimethylformamide (75ml.) was added to a stirred mixture of cuprous chloride (0.25g.), hydroxylamine hydrochloride (0.50g.), methanol (31ml.), N,N-dimethylformamide (50ml.) and 70% aqueous ethylamine (7.5 ml.), and the mixture was stirred under nitrogen while cooling to 0°C., during 1 hour. 1-Bromo-3-methyl-1-butyn-3-ol (1.50g.) in N,N-dimethylformamide (30ml.) was added during 1 hour. The mixture was allowed to warm to room temperature during 1 hour, and potassium cyanide (1.5g.) in water (20ml.) was added. The mixture was added to water (1 litre) and the steroid product collected by filtration, dried, and purified by crystallisation from aqueous methanol, giving 3-cyclopentyloxy-17 α -(5-hydroxy-5-methyl-1,3-hexadiynyl)-1,3,5(10)-oestratrien-17 β -ol, m.p. 142-145°C., $[\alpha]_D^{23}$ - 35.8° (C, 0.40 in chloroform), λ_{max} 223 nm (ϵ , 9400), 280 nm (ϵ , 1875), λ_{inf} 259 nm (ϵ , 581).

Example 17

17α -(5-Hydroxy-5-methyl-1,3-hexadiynyl)-4-androsten-17 β -ol-3-one

The 3oxime of 17α -ethynyl-4-androsten- 17β -ol-3-one (17.00g.) in N,N-dimethylformamide (350ml.) was added to a stirred mixture of cuprous chloride (1.25g.), hydroxylamine hydrochloride (2.50g.), methanol (156ml.), N,N-dimethylformamide (250ml.) and 70% aqueous ethylamine (37.5ml.), and the mixture was stirred under nitrogen while cooling to 0°C. during 1 hour. 1-Bromo-3-methyl-1-butyn-3-ol (7.50g.) in N,N-dimethylformamide (150ml.) was added during 1 hour. The mixture was allowed to warm to room temperature during 1 hour and potassium cyanide (0.75g.) in water (10ml.) added. The mixture was poured into water (4 litres) and the steroid product collected by filtration. Crystallisation from aqueous methanol gave the oxime m.p. 240-241°C.

A mixture of the oxime (8.00g.), glacial acetic acid (40ml.), pyruvic acid (6.24g.), sodium acetate (3.04g.) and water (16 ml.) was refluxed for four hours, and poured into water (650ml.). The steroid product was collected by filtration and purified by crystallisation from aqueous methanol, giving 17α -(5-hydroxy-5-methyl-1,3-hexadiynyl)-4-androsten- 17β -ol-3-one, m.p. 237°C., $[\alpha]_D^{26}$ -34° (c, 0.41 in dioxan), λ_{max} 240 nm (ϵ , 15728).

Example 18
 17α -(5-Hydroxy-5-methyl-1,3-hexadiynyl)-4-oestren- 17β -ol-3-one

17α -Ethynyl-3-methoxy-3,5-oestradien- 17β -ol (13.6g.) in N,N-dimethylformamide (340ml.) was added to a stirred mixture of cuprous chloride (1.13g.), hydroxylamine hydrochloride (3.40g.), methanol (142ml.), N,N-dimethylformamide (226.5ml.) and 70% aqueous ethylamine (34ml.) and the mixture was stirred at room temperature under nitrogen for 5 min. and then cooled to 0°C. 1-Bromo-3-methyl-1-butyn-3-ol (6.80g.) in N,N-dimethylformamide (136ml.) was added during 1 hour. The mixture was allowed to warm to room temperature, stirred for 75 min., and poured into water (4.5 litres). The steroid product was isolated by extraction with ether and treated in refluxing methanol (800 ml.) with p-toluenesulphonic acid (2.08g.) and water (5.5ml.) for 10 min. The methanolic solution was poured into water and the steroid product collected by filtration, dried, and purified by chromatography on alumina, eluting with toluene/ether, and by crystallisation from cyclohexane/ether, giving 17α -(5-hydroxy-5-methyl-1,3-hexadiynyl)-4-oestren- 17β -ol-3-one, m.p. 131-143°C., $[\alpha]_D^{25}$ -80.5° (c, 0.58 in dioxan), λ_{max} 239.5 nm (ϵ , 14800).

Example 19
 17α -(5-Hydroxy-5-methyl-1,3-hexadiynyl)-5-androsten- $3\beta,17\beta$ -diol

17α -Ethynyl-5-androstone- $3\beta,17\beta$ -diol (7.00g.) in N,N-dimethylformamide (150ml.) was added to a stirred mixture of cuprous chloride (0.50g.), hydroxylamine hydrochloride (1.00g.), methanol (6.25ml.), N,N-dimethylformamide (100ml.) and 70% aqueous ethylamine (15 ml.), and the mixture was stirred under nitrogen while cooling to 0°C. during 30 minutes. 1-Bromo-3-methyl-1-butyn-3-ol (3.00g.) in N,N-dimethylformamide (60ml.) was added during 1 hour. The mixture was allowed to warm to room temperature during 1 hour, and potassium cyanide (3.0g.) in water (40 ml.) was added. The mixture was poured into water (2 litres) and the steroid product was collected by filtration, dried, and purified by crystallisation from aqueous methanol and from ether/light petroleum giving 17α -

(5-hydroxy-5-methyl-1,3-hexadiynyl)-5-androsten- $3\beta,17\beta$ -diol, m.p. 209°C. $[\alpha]_D^{27}$ -145°(c, 0.54 in dioxan).

We claim:

5 1. A compound having sex hormonal activity selected from the group consisting of steroid compounds of the androstan- α of oestrane series possessing a 17β -hydroxy, lower alkoxy or lower alkanoyloxy group and being substituted in the 17α -position by a group of the

10 structure

wherein

R^1 is selected from the group consisting of carbocyclic aryl, benzyl, phenethyl, 2-pyridyl, 3-pyridyl, 2-thienyl, 3-thienyl, alicyclic, and alkenyl having 2-5 carbon atoms;

R^2 is selected from the group consisting of hydrogen, carbocyclic aryl, benzyl, phenethyl, 2-pyridyl, 3-pyridyl, 2-thienyl, 3-thienyl, alicyclic, alkenyl having two-five carbon atoms and alkyl having 1-5 carbon atoms; or

R^1 and R^2 together with the carbon atoms to which they are attached form an alicyclic ring.

20 2. A compound as defined in claim 1 having an oxygen function at the 3-position.

25 3. A compound as defined in claim 1 possessing olefinic or aromatic unsaturation in ring A.

40 4. A compound as defined in claim 1 wherein said 17β -oxygen function is a hydroxy group.

5. A compound as defined in claim 1 wherein R^1 or R^2 is selected from the group consisting of phenyl, 1-naphthyl, 2-naphthyl, o-biphenyl and p-biphenyl groups, and groups of this character substituted by at least one member selected from the group consisting of fluorine, chlorine, bromine, hydroxy, C_1C_5 alkyl, C_1C_5 alkoxy and trifluoromethyl groups.

45 6. A compound as defined in claim 1 wherein R^1 is selected from the group consisting of cyclohexyl, adamantyl, vinyl, propenyl and isopropenyl; and

50 7. A compound as defined in claim 1 selected from the group consisting of

- 17α -(5-hydroxy-5-phenyl-1,3-pentadiynyl)-3-methoxy-1,3,5(10)-oestratrien- 17β -ol;
- 17α -(5-hydroxy-5-p-tolyl-1,3-pentadiynyl)-3-methoxy-1,3,5(10)-oestratrien- 17β -ol;
- 17α -(5-hydroxy-5-(2-naphthyl)-1,3-pentadiynyl)-3-methoxy-1,3,5(10)-oestratrien- 17β -ol;
- 17α -(5-hydroxy-5-o-chlorophenyl-1,3-pentadiynyl)-3-methoxy-1,3,5(10)-oestratrien- 17β -ol;
- 17α -(5-hydroxy-5,5-diphenyl-1,3-pentadiynyl)-3-methoxy-1,3,5(10)-oestratrien- 17β -ol;
- 17α -(5-hydroxy-5-phenyl-1,3-pentadiynyl)-6 β -methyl- 5α -androstan- $3\beta,5,17\beta$ -triol;
- 17α -(5-hydroxy-5-(1-naphthyl)-1,3-pentadiynyl)-3-methoxy-1,3,5(10)-oestratrien- 17β -ol;
- 17α -(5-hydroxy-5-cyclohexyl-1,3-pentadiynyl)-3-methoxy-1,3,5(10)-oestratrien- 17β -ol;

15

17α -(5-hydroxy-5-*o*-methoxyphenyl-1,3-pentadiynyl)-3-methoxy-1,3,5(10)-oestratrien- 17β -ol;
 17α -(5-hydroxy-5-*p*-biphenyl-1,3-pentadiynyl)-3-methoxy-1,3,5(10)-oestratrien- 17β -ol;
 17α -(5-hydroxy-5-*p*-methoxyphenyl-1,3-

16

pentadiynyl)-3-methoxy-1,3,5(10)-oestratrien- 17β -ol; and
 17α -(5-hydroxy-5-phenyl-1,3-pentadiynyl-1,3,5(10)-oestratrien-3, 17β -diol.
